UNITED STATES PATENT OFFICE.

WARREN C. RAUB, OF ST. LOUIS, MISSOURI.

CHAIN PROPELLER.

SPECIFICATION forming part of Letters Patent No. 643,752, dated February 20, 1900.

Application filed June 15, 1899. Serial No. 720,697. (No model.)

To all whom it may concern:

Be it known that I, WARREN C. RAUB, a citizen of the United States, residing at St. Louis, State of Missouri, have invented certain new 5 and useful Improvements in Paddle-Wheels, of which the following is a full, clear, and exact description, reference being had to the accompanying drawings, forming a part hereof.

My invention has relation to improvements 10 in paddle-wheels for boat propulsion; and it consists in the novel arrangement and combination of parts more fully set forth in the specification and pointed out in the claim.

In the drawings, Figure 1 is a side elevation 15 of the invention. Fig. 2 is an enlarged section on line 2 2 of Fig. 3, showing two consecutive blades in their travel about the wheel-periphery. Fig. 3 is an elevation of one of the blades and rings embracing the same, the 20 cables being shown in section and the "tooth" of the sprocket-wheel dotted, the blade being broken partly away; and Fig. 4 is a detail of a cable-tightener.

The object of my invention is to construct 25 a paddle-wheel in which the blades shall for the major portion of their travel in the water move at a tangent to the periphery of the wheel, irrespective of the length of the diameter of said wheel. By this arrangement the 30 blade travels through the water in a direction at right angles to the surface of the blade, thereby utilizing to the best advantage the reactionary force of the water and increasing the efficiency of the wheel to a maximum.

35 In detail the invention may be described as follows:

Referring to the drawings, 1 represents one 40 of the side timbers of a vessel adapted to support the shafts 2, 2', and 2" of the paddle-drums and intermediate crank-arm, respectively.

3 represents the engine; 4, a pitman; 5, the 45 crank-arms of the drums 6 6, and 5' the intermediate crank-arm, which is connected to the arms 5 5 by a connecting-rod 4'. Disposed along the periphery of each drum 6, in lines 50 parallel to the axis of rotation thereof, are a series of ridges 7, performing the function of sprocket-teeth, the outer edge of each ridge 55 being provided with a series of forked brackets 8, designed to receive the endless cables 9, by which the blades are carried. Each cable

passes through the medial longitudinal line of the respective blades 10, the latter being centrally confined within a series of metallic 55 rings or bands 11, to which the blades are secured through the medium of an angle iron or bar 12, the deflected terminal ends or arms of which are riveted to the inside of the ring 11. (See Fig. 2.)

60 Provision may be made for tightening the cable, as seen in detail in Fig. 4, where the free ends of the cable 9 are secured to the opposite ends of an oblong loop 15, one of the free ends of the cable being connected to a screw-threaded bolt 16, over which is passed a tightening-nut 17, normally bearing against two or more ribs 18, formed with the loop. By turning the nut in proper direction it is obvious the cable may be tightened. The length 70 of any blade or board 10 will of course depend on the length of the wheel, and in Fig. 3 the board is shown broken away, indicating that its length is indefinite.

75 Each board or blade is directly secured to the bar 12 by bolts, as best seen in Fig. 2, this view showing a series of two blades the connecting-cable of which is shown as passing over one of the "teeth" of the sprocket-drum 6. In Fig. 1 the endless cable and blades are 80 shown diagrammatically without an attempt to bring out the details shown in Fig. 2.

Whether the engine drives the drums 6 6 in one direction or the other it is obvious that the lower series of blades (which are always 85 submerged in the water) will travel in a direction tangent to the peripheries of the drums and at right angles to the planes of their faces, the latter always bearing squarely against the water during their passage therethrough, and 90 this whether the drums 6 6 are large or small. In the ordinary paddle-wheel in order to approximate the results here attained there would have to be constructed a paddle-wheel of unusual dimensions, as with a small wheel 95 the "tangent" movement would be limited to a very small portion of the blade's travel in the water.

100 It is apparent that the device might be altered in many details without departing from the spirit of my invention. The ridges 7 have their opposite faces concave, so as to accommodate the curvature of the rings or bands 11, which bear against them, this arrange-

ment serving to retain the blades approximately in the planes of the radii of the drums and cause them to leave the drums in a tangent to their peripheries.

5 In the present construction the drums serve to support the entire length of each blade as the latter passes over the same, and the intermediate series of cables serve to stiffen each blade as the latter is drawn through the water.

10 It is obvious that the present invention may be utilized for the generation of power by partially submerging the wheel below the surface of a running stream or current, the resistance of the blades to the current resulting in motion of the entire series, and consequent rotation of the drums by which the paddles are connected. From the shafts of the drums it is apparent that the power can be conveyed to any suitable machinery.

15 20 Having described my invention, what I claim is—

A paddle - wheel comprising two drums, means for rotating the same, ridges having concave faces, disposed about the peripheries 25 of the drums in lines parallel to the axes there-

of, forked brackets disposed along the outer longitudinal edges of the ridges, a series of blades of substantially the full length of the drums, a series of circular rings surrounding each blade and distributed at intervals along 30 the length thereof, the rings being positively supported by the concave faces of the ridges during the rotation of the drums, and insuring the retention of the blades in lines parallel to the radii of the drums, angle-bars for 35 securing each blade centrally within the series of rings, endless cables passing through each board, angle-bar, and ring, and traveling over the forked brackets disposed along the ridges, the blades between the drums traveling substantially in a path tangential to the peripheries of the drums, and means for tightening the cables, substantially as set forth.

In testimony whereof I affix my signature in presence of two witnesses.

WARREN C. RAUB.
